CLOTHES POLE

Richard J. S. Hoppe, Maplewood, Mo.

Application September 17, 1947, Serial No. 774,651

3 Claims. (Cl. 248—343)

1

This invention relates to clothes poles, and has for its principal object the production of a pole which will permit the hanging of clothes upon a line in association therewith, and the raising and lowering of the line, without the stretching and effort on the part of the operator which are necessary with the use of the ordinary clothes pole as heretofore made.

In the use of clothes poles as previously known, the line associated therewith must be stretched very tautly, for unless it is the clothes pole will easily become disengaged therefrom, and this tautness makes it an arduous task to raise the line when the clothes have been hung. For this reason it is necessary that the line be stretched at such a height that it requires a considerable amount of stretching and reaching on the part of the operator to place the clothes thereon, and also a good deal of strength must be used to raise the taut line still higher in order to insure sufficient clearance between the clothes and the ground. These movements are particularly injurious to women, and frequently result in damage to the delicate internal organs of the person hanging the clothes.

Through the use of my new clothes pole all this reaching and stretching is avoided. When the line has been stretched at a height which is within easy reach of the operator, my pole is simply placed in association with the line as will be later described, and by merely turning the pole it is so securely engaged with the line that there is no danger of its becoming disengaged; and since the line in the first place has not been stretched so tautly, it does not require as much strength to push it up to the desired height.

Additional advantages of my clothes pole are that it is light in weight, being preferably formed almost entirely of aluminum, and it has no parts that can be damaged or get out of order with ordinary usage. It is simple in construction, and therefore can be cheaply and quickly produced at low cost. It does not require any expensive or special clothesline, but is intended for use with the ordinary line which is in general use for this purpose.

In the drawings—

Fig. 1 is an elevational view of my clothes pole on a reduced scale.

Fig. 2 is a longitudinal, sectional view, partly broken away, illustrating particularly the locking means of my pole.

Fig. 3 is a cross-sectional view taken on the line 3—3, Fig. 2.

Fig. 4 is an elevational view of my clothes pole

as it appears when in operating engagement with a clothesline.

Fig. 5 is a view similar to Fig. 4 but taken from a different angle.

Fig. 6 is a top plan view of the pole in operative engagement with a clothesline.

The invention comprises a pole 1 formed of tubular metal, preferably aluminum for the sake of its light weight, and open at both ends, and a comparatively short, cylindrical member 2 of slightly less diameter than the pole 1 is mounted in the upper end of the pole and rigidly secured in position by a rivet 3. The member 2 extends beyond the top of the pole, and at its upper end flares outwardly to the point shown at 4, where its diameter is greater than the diameter of the pole 1. The cylindrical member 2 is provided with grooves 5 for a purpose to be hereinafter set forth.

A circular member 6 having a vertical, circumferential wall 7 is mounted around the top of the cylindrical member 2, and said circular member is bifurcated to form two upstanding arms 8 so shaped that their lower portions are curved outwardly to meet the top edge of the vertical wall 7, as most clearly shown in Fig. 2, and leaving a groove 8a between the arms 8. The circular member 6 has inwardly extending lugs 9 which register with the grooves 5 and are secured therein in any suitable manner to provide a rigid connection between said bifurcated member and the cylindrical member 2.

A peculiarly shaped circular element 10 surrounds the member 2 and is positioned between the tubular pole 1 and the member 6. The element 10 has a central aperture of slightly greater diameter than the member 2 and is adapted to be seated upon the top edge of the tubular pole 1, as at 11. The element 10 flares outwardly to the point indicated at 12, where it forms a narrow vertical wall 13. At regularly spaced intervals the wall 13 has a plurality of upwardly extending ears 14, each of which terminates at its upper end in a slightly rounded point 15 and is shaped to form a short curved section 16, which meets the edge of the wall 13. The shape of the ears 14 is most clearly illustrated in Figs. 4 and 5.

At the center of its upper surface the element 10 is provided with a circular cut-out portion 17 of the same depth and diameter as the wall 7 of the bifurcated element 6, and the element 10 has a pair of lugs 18 which extend inwardly from its central aperture 17 into the grooves 5 of the member 2, so that by virtue of the engagement of said lugs 18 and grooves 5 the element 10 is longitudinally slideable upon the cylindrical member 2.

and at the same time prevented from rotating thereon.

At the lower open end of the tubular pole 1 a plug 19 is inserted thereinto and permitted to extend for a short distance beyond the pole. The plug 19 is secured within the pole by means of a rivet 20, and its end which extends beyond the pole is of rounded contour, as shown in Fig. 1, to facilitate its gripping engagement with the ground when in use.

In operation the procedure is as follows:

Suppose an ordinary clothesline L has been stretched at a height that is within easy reach of the person hanging out clothes. When the clothes have been placed thereon, and the line is to be raised, the pole is placed in position so that a section of the line L rests within the groove 8a. Gripping the pole 1 the operator turns it approximately a half-turn or a little more to the right and then pushes the element 10 upwardly on the member 2 until the wall portion 7 of the member 6 is seated in the aperture 17, and then turns the pole slightly in the opposite direction, which has the effect of catching the line L in the curved sections 16 of the ears 14, where it is securely locked, the ends 15 preventing the line from slipping out of the curved sections. The line L is now in firm interlocking engagement with the pole and may be raised by pushing the upper end of the pole to the desired height. The plug 19 is placed in gripping engagement with the ground, and the entire assembly is firmly held in position and proof against accidental disengagement of the line L from the pole.

When the pole is to be removed from the line, it is merely turned to the right approximately one-fourth of a turn, which disengages the line L from the ears 14, allowing the member 6 to drop to its seat upon the top of the pole 1. Then by loosening of the operator's grip on the pole, the pole will turn to the left due to the pressure of the line L around the arms 8, and the line will be fully released from engagement with the pole.

I claim:

1. A clothes pole adapted to be associated with a clothesline, and comprising a pole having at its

upper end a cylindrical member surmounted by a bifurcated member for engagement with said clothesline, and an element surrounding said cylindrical member and slideable thereon, said element having means for engagement with said clothesline adapted to prevent disengagement of said clothesline from said pole.

2. A clothes pole adapted to be associated with a clothesline, and comprising a pole having at its upper end a grooved cylindrical member surmounted by a bifurcated member for engagement with said clothesline, and an element surrounding said cylindrical member and provided with means in registration with the grooves thereof to render said element and said cylindrical member slideable but not rotatable with respect to each other, said element having means for engagement with said clothesline adapted to prevent disengagement of said clothesline from said pole.

3. A clothes pole adapted to be associated with a clothesline, and comprising a pole having at its upper end a grooved cylindrical member surmounted by a bifurcated member for engagement with said clothesline, portions of said bifurcated member being rigidly secured in the grooves of said cylindrical member, and an element surrounding said cylindrical member and provided with means in registration with the grooves thereof to render said element and said cylindrical member slideable but not rotatable with respect to each other, said element having means for engagement with said clothesline adapted to prevent disengagement of said clothesline from said pole.

RICHARD J. S. HOPPE.
